CLAIM

We claim the ornamental design for a manufactured siding panel with frame, as shown and described.

DESCRIPTION

FIG. 1 is a front isometric view of a manufactured siding panel with frame, the broken lines depicting portions of the siding panel that form no part of the claim.

FIG. 2 is a rear isometric view of the siding panel of FIG. 1, the broken lines depicting portions of the siding panel that form no part of the claim.

FIG. 3 is a left side view of the siding panel of FIG. 1, the broken lines depicting portions of the siding panel that form no part of the claim.

FIG. 4 is a front view of the siding panel of FIG. 1, the broken lines depicting portions of the siding panel that form no part of the claim.

FIG. 5 is a rear view of the siding panel of FIG. 1, the broken lines depicting portions of the siding panel that form no part of the claim; and,

FIG. 6 is a right side view of the siding panel of FIG. 1, the broken lines depicting portions of the siding panel that form no part of the claim.

1 Claim, 4 Drawing Sheets

Related U.S. Application Data

application No. 14/060,318, filed on Oct. 22, 2013,
now Pat. No. 9,169,652.
